United States Patent Office.

ROBERT W. SOPER, OF JANESEVILLE, WISCONSIN, ASSIGNOR TO HIMSELF
AND FRANK RICHARDS, OF SAME PLACE.

Letters Patent No. 69,942, dated October 15, 1867.

IMPROVED MOP-WRINGER.

The Schedule referred to in these Letters Patent and making part of the same.

TO ALL WHOM IT MAY CONCERN:

Be it known that I, ROBERT W. SOPER, of the city of Janesville, in the county of Rock, and State of Wisconsin, have invented a new and improved Mop-Wringer; and I do hereby declare that the following is a full and exact description thereof, reference being had to the accompanying drawings, making a part of this specification, in which—

Figure 1 is an elevation or side view, showing the rolls in position ready for wringing.

Figure 2 is also an elevation or side view, showing the device in the act of wringing.

Figure 3 is a view from the back or inner side of the cam-piece E, operating-levers D and D', and guide support F; and

Figure 4 is a view from the back or inner side of the cam-piece E detached.

The nature of my invention relates to that class of mop-wringers that have two parallel wringing-rolls attached to a pail or tub, and consists in supporting them on the upper ends of four operating-levers that are arranged in pairs on either side of the pail, each pair having a common central pivot like a pair of shears, and being operated by a vertical moving cam-piece attached to a treadle, the cam-piece having two fixed cam-pins working separately in a cam-groove in the lower end of each member of the pair, substantially as described.

To enable others skilled in the art to make and use my invention, I will proceed to describe its construction and operation.

In the drawings, A represents the pail or tub, and C and C' the two parallel wringing-rolls. These rolls are placed horizontally with reference to each other, and take bearing at each end in the upper ends of the operating-levers D D' that are coupled together in pairs on each side of the pail, each pair having a common central pivot, b, like a pair of shears. The lower end of each operating-lever is pierced or cut with a cam-groove, f, in which plays a cam-pin, h, figs. 3 and 4, of the cam-piece E that is attached by the pivot pin d to the treadle G. The treadle is provided with a foot-piece, H, on which the foot is applied to operate the rolls, and is divided at the foot-piece into two arms that curve on either side around the pail, and have their ends attached to and working on the pivoted ends g of a yoke, I, that is secured by screws or rivets in a horizontal position on the back side of the pail. To prevent the cam-piece E from inclining over sideways, and thereby operating the rolls irregularly, I attach, by means of screws or rivets e to the side of the pail and underneath the cam, a guide-piece, F, that is provided with a vertical groove or mortise, e, in which plays the rectangular guide-pin i that is attached to and makes a part of the cam E. To prevent the pail from tipping over when the wringer is used, I attach in the front and at the bottom thereof a foot, J, as shown. To separate the rolls I employ on either side of the pail a spring, M, that has its lower end attached to an arm of the treadle G, and its upper to a hook or staple near the top of the pail.

To operate my mop-wringer it is only necessary to place the mop L, fig. 2, between the rolls C C', and to press down the treadle G by applying the foot to the foot-piece H. The treadle G in its downward movement swings upon the pivoted ends g of the yoke I and takes down with it the cam-piece E, that, by means of the cam-pins h and cam-grooves f, drives together the ends of the operating-levers D D' after the manner of a pair of shears, and so presses the rolls C and C' against the mop, which, upon being withdrawn, is found to be wrung. Upon removing the foot from the treadle the latter is again raised and the rolls separated by the spring M.

What I claim, is—

1. The arrangement of the supporting-levers D and D' with the cam-piece E (the former being provided with the cam-grooves f and the latter with the cam-pins h) in such a manner that the vertical movement of the cam-piece shall operate the wringing-rolls C and C', substantially as described.
2. The construction of the cam-piece E and guide F, with the rectangular guide-pin i and vertical groove or mortise e, substantially as and for the purpose described.
3. The arrangement of the treadle G pivoted on the ends of the yoke I with the cam E, operating-levers D D', and spring M, when the whole are constructed and used substantially as described.
